INVENTOR,
JOHN H. REYNOLDS.
By Martin O'Smith,
Atty.

UNITED STATES PATENT OFFICE.

JOHN H. REYNOLDS, OF LOS ANGELES, CALIFORNIA.

FLYING MACHINE.

Application filed May 22, 1924. Serial No. 715,084.

To all whom it may concern:

Be it known that I, JOHN H. REYNOLDS, citizen of the United States, residing at Los Angeles, in the county of Los Angeles and State of California, have invented certain new and useful Improvements in Flying Machines, of which the following is a specification.

My invention relates to a flying machine of the "heavier than air" type, the principal objects of my invention being to provide a flying machine with fore and aft screw propellers that will be effective in driving the machine in a general horizontal plane and, to provide the machine with a centrally arranged member that is arranged to rotate in a horizontal plane, and said member being provided with vanes or wings that are adapted to impinge the air so as to produce a lifting effect and cause the machine to rise in a practically perpendicular path, after the manner of a helicopter.

Further objects of my invention are, to construct the flying machine so that the horizontally rotative member that carries the lifting vanes or wings will perform the functions of a stabilizer while the machine is travelling in a horizontal plane and, in addition, said rotative member will function as a sustaining plane or parachute, to prevent the machine from dropping or moving downward at a dangerous speed, in the event of failure of the engine or driving mechanism to function properly.

Further objects of my invention are, to generally improve upon and simplify the construction of the existing forms of flying machines; to provide relatively simple and easily manipulated means for guiding or turning the machine laterally during flight; and further, to provide a machine that may be easily and cheaply produced and which will be very effective in performing its intended functions.

With the foregoing and other objects in view, my invention consists in certain novel features of construction and arrangement of parts that will be hereinafter more fully described and claimed and illustrated in the accompanying drawings in which—

Fig. 1 is a side elevational view of my improved flying machine with parts thereof in section.

Fig. 2 is a horizontal section taken approximately on the line 2—2 of Fig. 1.

Fig. 3 is a top plan view of the horizon-

tally rotative member that carries the lifting vanes or wings.

Fig. 4 is an enlarged cross sectional view taken approximately on the line 4—4 of Fig. 1.

Referring by numerals to the accompanying drawings, 10 designates the body of the machine, the same being pointed at both ends, after the manner of a boat, and said body being open at its top, throughout its entire length. The greater portions of the pointed ends of the body are open at their bottoms and depending from the central portion of the body 10 and between the open lower end portions is a cabin or cockpit 11, that contains the power plant, preferably an internal combustion engine, the steering levers and other control mechanisms.

A post 13 projects upwardly from the central portion of the bottom of cabin 11, and arranged for rotation thereon is a sleeve 14, that is driven directly from the engine 12, preferably by bevelled pinions 15.

The lower end of this sleeve is suitably journaled in a step bearing 16, and the intermediate portion of said sleeve is journaled in a suitable anti-friction bearing 17 that is carried by a bar 18 that is transversely arranged at the top of body 10.

A longitudinally disposed shaft 19 is journaled in suitably located bearings 20 on the front portion of body 10 and carried by the forward end of said shaft that projects beyond the front end of said body is a screw propeller 21, having a plurality of spirally disposed blades.

The inner end of shaft 19, which terminates adjacent to sleeve 14 is made square in cross section or provided with a key or feather and arranged for sliding movement upon this portion of said shaft is a bevelled pinion 22 that is adapted to be moved into and out of mesh with a bevelled pinion 23, that is secured to sleeve 14.

A longitudinally disposed shaft 24, similar to shaft 19 is mounted to rotate in suitable bearings 25 on the rear portion of body 10, and the outer end of said shaft that projects beyond the rear end of said body carries a screw propeller 26, of the type having a plurality of spirally arranged blades.

Mounted to rotate with and slide longitudinally upon the inner end of this shaft 24, is a bevelled pinion 27, that is adapted to be moved into and out of engagement with pinion 23.

- The driving connections between sleeve 14 rotary member 32 may be counteracted by and shafts 19 and 24 enable either shaft to be driven independently or both shafts to be driven simultaneously.
- 5 Centrally arranged beneath the open end portions of the body 10 are vertically disposed longitudinally extending rudders 28, that are connected near their outer ends to vertically disposed rudder posts 29. These 10 posts are journaled in suitable bearings 30 at the ends of body 10 and the upper ends of said posts are provided with suitable cross arms or levers 31 to which may be connected, suitable rudder actuating mechanism.
- 15 These rudders are located beneath the open end portions of the body 10 and said rudders extend from the ends of said body inwardly to points adjacent to the end walls of cabin 11.
- 20 Secured to the upper end of sleeve 14 is a large disc-shaped member 32 having its marginal portion 33 curved downwardly and this said member has the general shape of an inverted pan or saucer.
- 25 Secured to the downwardly curved portion of this inverted pan-shaped member is a series of inclined blades or vanes 34 that extend outwardly and upwardly from said curved marginal portion and said vanes are 30 spaced at equal distances apart.
- 35 Mounted on standards or brackets 35 that project upward from the flat central portion of member 32 is a pair of horizontally disposed planes or vanes 36, the members thereof being disposed on opposite sides of the center of said member 32 and said planes being inclined in cross section so as to impinge the air and exert lifting effort when member 32 is rotated.
- 40 In the operation of my improved flying machine, engine or motor 12 is started and through driving connections 15, sleeve 14 and member 32 on the upper end thereof are rotated.
- 45 When a certain speed of rotation is attained, the impingement of the under surfaces of the inclined vanes 34 and 36 produces a lifting effect that causes the machine to leave the ground and rise in practically a perpendicular path.
- 50 When the machine has reached the desired height, pinions 22 and 27 are thrown into mesh with the bevelled pinion 23 on sleeve 14 and, as a result shafts 14 and 24 carrying the propellers 21 and 26 will be rotated.
- 55 The impingement of the blades of the propellers 21 and 26 against the air will drive the machine forwardly and by proper manipulation of the rudders or steering planes 28, the machine may be guided laterally during its forward flight.
- 60 Any tendency of the body of the ship to rotate on the vertical axis comprising post 13 and sleeve 14 as a result of the action of
- proper "setting" of the rudders 28.
- 65 By proper manipulation of pinions 22 and 27 upon their respective shafts, the operation of the latter and their propellers 70 may readily be controlled.
- Inasmuch as rotary member 32 has considerable area and is of umbrella or inverted saucer shape, it will act as a parachute, to prevent the machine from a too sudden 75 descent in the event that the motor, or operating parts of the machine are, from any cause, rendered inoperative.
- This particular effect is particularly effective, due to the fact that both ends of the 80 body 10 are open, thereby permitting free passage of air upwardly through the ends of the machine into the chamber beneath member 32.
- If desired the underside of cabin 11 may 85 be provided with longitudinally disposed runners 37, and the end portions thereof may be extended upward to the end portions of the side walls of the body 10, thereby providing struts or braces 38.
- 90 In some instances it may be found desirable to provide a single propeller shaft to take the place of the two shafts 19 and 24, and when this is done, said single shaft will 95 extend alongside sleeve 14 and suitable driving connections will be arranged between said shaft and sleeve.
- 98 Thus it will be seen that I have provided a relatively simple, practical and easily 100 manipulated flying machine which, in operation, may be caused to rise from the ground after the manner of a helicopter and then driven in a substantially horizontal plane and the lifting element of the machine being constructed so that, under certain conditions, it will function as a parachute, thereby giving to the occupants of the machine an added factor of safety.
- 105 It will be understood that minor changes 110 in the size, form and construction of the various parts of my improved flying machine may be made and substituted for those herein shown and described without departing from the spirit of the invention, the 115 scope of which is set forth in the appended claims.
- 118 I claim as my invention:
1. In a flying machine, a body, longitudinally disposed shafts journaled on said body and projecting beyond the ends thereof, screw propellers on the projecting ends of said shafts, a vertically disposed shaft journaled in the center of said body, an inverted saucer-shaped member carried by the upper end of said shaft and inclined vanes arranged on the upper portion of said inverted saucer-shaped member.
- 125 2. In a flying machine, a body, longitudinally disposed shafts journaled on said body and projecting beyond the ends there-

- of, screw propellers on the projecting ends of said shafts, a vertically disposed shaft journalled in the center of said body, an inverted saucer-shaped member carried by the upper end of said shaft, inclined vanes arranged on the upper portion of said inverted saucer-shaped member, means for driving said vertically disposed shaft, and driving connections between said vertically disposed shaft and the propeller carrying shafts.
3. In a flying machine, an elongated body having a centrally arranged depending cabin, rudders arranged beneath the end portions of said body in front and to the rear of said cabin, independently operable shafts mounted for rotation on said body and projecting beyond the ends thereof, screw propellers on the projecting ends of said shafts, a vertically arranged shaft mounted for rotation on said body, an inverted saucer-shaped member carried by the upper end of said vertically arranged
- 5 shaft and inclined vanes on the upper side of said saucer-shaped member. 25
4. In a flying machine, an elongated body having a centrally arranged depending cabin, rudders arranged beneath the end portions of said body in front and to the rear of said cabin, independently operable 30 shafts mounted for rotation on said body and projecting beyond the ends thereof, screw propellers on the projecting ends of said shafts, a vertically arranged shaft mounted for rotation on said body, an inverted saucer-shaped member carried by the upper end of said vertically arranged 35 shaft, inclined vanes on the upper side of said saucer-shaped member and means for driving said vertically disposed shaft and 40 driving connections between said vertically disposed shaft and the propeller-carrying shafts.

In testimony whereof I affix my signature.

JOHN H. REYNOLDS.
